UNITED STATES PATENT OFFICE.

SAMUEL SEGAL, OF NEW YORK, N. Y., ASSIGNOR TO SAMUEL SEGAL & COMPANY, OF NEW YORK, N. Y., A COPARTNERSHIP COMPOSED OF SAMUEL SEGAL AND HARRY MODEL.

PADLOCK.

Application filed March 18, 1925. Serial No. 16,271.

This invention has for its principal object the production of a padlock which may be easily assembled and which shall be simple in construction. Although the invention is not to be so limited, I prefer to employ in conjunction therewith a pin-tumbler mechanism actuated by a key for releasing the shackle or a leg thereof from the body of the padlock.

10 A further object of the invention is the production of a padlock in which the means for holding the shackle in closed or locked position is carried by the shackle itself.

15 Further objects and advantages of the invention will appear from the accompanying description, the invention consisting in the novel padlock hereinafter more particularly described and then specified in the claims.

20 In the accompanying drawings illustrating a practical embodiment of the invention:

Fig. 1 is a top plan view of the padlock.

Fig. 2 is a side elevation thereof.

Fig. 3 is a horizontal section on the line 3—3 of Fig. 2.

25 Fig. 4 is a section taken through the padlock on the line 4—4 of Fig. 1 showing the shackle in closed position.

Fig. 5 is a similar view but showing the shackle in open position.

30 Fig. 6 is a side elevation of a modification.

Fig. 7 is a horizontal section on the line 7—7 of Fig. 9.

Fig. 8 is a horizontal section on the line 8—8 of Fig. 10.

35 Fig. 9 is a section taken through the padlock showing the shackle in closed position.

Fig. 10 is a similar view showing the shackle in open position.

40 Referring in detail to the several figures of the drawings:

1 indicates the hollow body or casing of the padlock which is provided with bores or openings in the upper wall thereof receiving the long and short legs 2 and 3 respectively of a shackle 4 as in the ordinary construction of devices of this character. The bore or opening for the long leg 2 is somewhat enlarged intermediate its ends to provide a chamber 5 forming an upper annular wall or shoulder 6 and a lower inclined or cam wall 7. The bore or opening for the short leg 3 is slotted as at 8 for a purpose to be presently described. The lower end of the long leg 2 is hollow as at 9 and receives

45 a spindle 10 seated in a suitable opening or

recess 11 formed in the body of the casing. 12 indicates a compression spring encircling said spindle and pressing upwardly against the long leg and tending by its action to force said long leg out of its bore or opening. The long leg 2 of the shackle is also provided with a recess 13 receiving a compression spring 14 which engages and presses outwardly a button 15 constituting a locking member, said button being provided 60 with an inner flange 16 engaging a shoulder adjacent the outer wall of the recess 13 to prevent said button from being projected out of said recess by the action of said spring 14. Likewise, the short leg is provided with 70 a similar recess 17, spring 18 and button 19.

When the shackle is in closed or locking position with the legs thereof entering their respective bores or openings, and as shown in Fig. 4, the button 15 engages a shoulder 20 on the lower edge or wall of the recess 5 and the button 19 projects through the slot 8 and engages a shoulder 21 on the lower side of the upper wall of the body of the padlock. Buttons 15 and 19 therefore constitute spring pressed locking elements or members carried by the shackle itself which act to effectively hold said shackle in locked and closed position against the action of the spring 12. When said buttons are pressed inwardly however they will clear their respective shoulders and the shackle will be forced upwardly by the action of the spring 12 whereby the short leg 3 of said shackle will be projected from the body or casing. 80 As soon as the button 15, however, clears the shoulder 20 it enters the recess 5 and is again projected outwardly by the action of the spring 14. It then engages the annular shoulder or wall 6 to prevent withdrawal of the long leg 2 of said shackle as shown in Fig. 5. To return the shackle to closed and locked position the short leg 3 is brought into alignment with its bore or opening and the shackle is then pressed downwardly against the action of the spring 12. When pressed downwardly the button 19 strikes an inclined or cam projection 21 formed on the upper wall of the body of the padlock which acts to force it inwardly until it reaches the slot 8 whereupon it is projected outwardly into locking position by the action of the spring 18 and again engages the shoulder 21. Likewise the button 15 engages the inclined or cam wall 7 90

95

100

105

110

and is forced inwardly thereby until it clears the lower portion of said wall whereupon it is projected into locking position and into engagement with the shoulder 20 by the action of the spring 14. It will furthermore be noted that the lower portion of the bore for the short leg 3 is provided with a plug 22 to prevent interference or manipulation with the interior mechanism of the padlock when the shackle is in open position.

One of the sides of the body of the padlock is provided with an annular opening 23 receiving a plate 24 which may be soldered or otherwise permanently secured within said opening. Said plate 4 carries the ordinary or conventional barrel 25 of a pin-tumbler lock in which is rotatably mounted the usual key plug or cylinder 26 adapted to be rotated by a proper key inserted in the key hole. The inner end of said key plug or cylinder is provided with an annular plate 27 which is secured thereto and which acts to prevent forward withdrawal of the cylinder through the barrel. Pivotally fastened to the barrel 25 is an actuating arm 28 which is held in normal position by a spring 29. 30 indicates a short actuating arm which is connected to or may be an integral part of the plate 27. The plate 27 also has connected thereto an arm 31 engaging the actuating arm 28. When the shackle is in closed position or the position shown in Fig. 4 and the key plug or cylinder 26 is rotated by means of the proper key the actuating arm 30 will engage the button 15 to release it from engagement with the shoulder 20 and simultaneously the arm 31 will press against the actuating arm 28 and cause said arm to swing on its pivot against the action of the spring 29 whereby the upper end or head of said arm 28 will enter the slot 8 and press against the button 19 to release it from engagement with the shoulder 21. The shackle will thereupon be thrown into open position by the spring 12 in the manner previously described.

In the modification illustrated in Figs. 6 to 10 inclusive I mount the pin-tumbler barrel which is indicated at 32 in the bottom of the body or casing of the padlock and fasten it thereto in any manner. The end of the key plug or cylinder is indicated at 33. The plate which is fastened to the inner end of the key plug or cylinder and which prevents withdrawal of said key plug from the barrel is indicated at 34. Said plate is provided with an end having inwardly extending walls 35 meeting each other and engaging an operating arm 36 which is pivoted as by pivot 37 to the lower ends of the walls of a slot 38 formed in the side of the barrel 32. In the modification I dispense entirely with the button or other locking means which is carried by the short leg of the shackle in the

preferred form of the invention but retain the button 15 which is mounted in the long leg and is similar in construction with the button in the long leg of the preferred form of the invention. When the key plug 33 is rotated by the proper key the operating arm 36 rides in a slot 38 due to its engagement with either of the inclined walls 35 thereby forcing the end of said operating arm against the button 15 to press said button inwardly whereby the shackle will be thrown into unlocked position by the action of the spring 12 in an obvious manner.

What I claim as my invention is:

1. In a padlock, a body, a shackle, a spring-pressed locking button carried by said shackle and adapted to engage said body to prevent withdrawal of said shackle from said body, a pin-tumbler barrel carried by said body and pivoted means for actuating said locking button upon rotation of said barrel.

2. In a padlock, a body, a shackle having two legs adapted to enter said body, a locking device carried by each of said legs for preventing withdrawal of said shackle from said body and means for simultaneously actuating said devices to permit withdrawal of one of said legs from said shackle, one of said locking devices acting as a stop to prevent withdrawal of the other of said legs from said body.

3. In a padlock, a body, a shackle adapted to enter said body, a locking device carried by said shackle for preventing withdrawal of said shackle from said body, a pin tumbler locking mechanism mounted in said body and means connected to said mechanism for actuating said locking device to permit partial withdrawal of said shackle from said body, said locking device acting as a stop to prevent complete withdrawal of said shackle from said body.

4. In a padlock, a body provided with openings, a shackle adapted to enter said openings, a cam projection on said body adjacent one of said openings and a spring-pressed locking button on said shackle adapted to engage said projection when said shackle is brought into closed position.

5. In a padlock, a body provided with openings therein and having a chamber communicating with one of said openings said chamber being provided with an inclined wall adjacent its lower end, a shackle adapted to enter said openings, a spring-pressed locking button carried by said shackle and adapted to engage the lower side of said chamber to hold the shackle in closed or locked position, said locking element also being adapted to engage the upper wall of said chamber to prevent complete removal of said shackle from said body and to ride against said inclined wall when the shackle is pressed into closed position.

6. In a padlock, a body provided with openings therein, a shackle adapted to enter said openings, a locking element carried by said shackle and adapted to engage said body to prevent removal of said shackle from said body, a pin-tumbler lock mechanism mounted in said body and an arm connected to said mechanism and adapted to actuate said locking element to permit said shackle to be brought into open position. 15
- 5 7. In a padlock, a body provided with openings therein, a shoulder on said body, a shackle adapted to enter said openings, a spring pressed button carried by said shackle and adapted to engage said shoulder to prevent removal of said shackle from said body, a pin-tumbler lock mechanism mounted in said body, an operating arm connected to said pin-tumbler lock mechanism and adapted to actuate said button to 20 release it from engagement with said shoulder whereby said shackle may be brought into open position. 25

Signed at New York in the county of New York and State of New York this 17th day of March A. D. 1925.

SAMUEL SEGAL.
